UNITED STATES PATENT OFFICE.

JOHN HUMPHRIES, OF KIDDERMINSTER, ENGLAND.

DESIGN FOR A CARPET-PATTERN.

Specification forming part of Design No. 5,904, dated June 4, 1872.

To all whom it may concern:

Be it known that I, JOHN HUMPHRIES, of Kidderminster, Worcestershire, in England, have invented a new and original Design for Carpets; and I do hereby declare that the following is a full, clear, and exact description thereof, which will enable others skilled in the art to make and use the same, reference being had to the accompanying photographic illustration forming part of the specification.

The nature of my design is fully represented in the accompanying photographic illustration, to which reference is made.

This invention relates to a new carpet design, which consists of rich floral bunches and tufts in which several fantastic flowers, leaves, and scrolls are arranged, as shown.

I claim as my invention—

The design for carpets, as shown.
